S. Anthony, Esq., ATTORNEY

UNITED STATES PATENT OFFICE.

JAMES H. GRAY, OF NEW YORK, N. Y.

ELECTRIC FURNACE AND METHOD OF SUPPLYING CURRENT THERETO.

1,278,635.

Specification of Letters Patent. Patented Sept. 10, 1918.

Application filed July 20, 1918. Serial No. 245,843.

To all whom it may concern:

Be it known that I, JAMES H. GRAY, a citizen of the United States, residing in the city, county, and State of New York, have 5 invented certain new and useful Improvements in Electric Furnaces and Methods of Supplying Current Thereto, of which the following is a specification:

My invention relates to electric furnaces 10 and more particularly to the method and means of controlling and supplying the current and preventing excessive surges in the fluctuations of the current and interruption of the arc during the melting down period. 15 In electric furnaces for melting down and refining metals by the utilization of heat from electric arcs it is desirable to employ a different E. M. F. during the melting period from that used during the refining 20 and finishing period. During the finishing period the metal is in the form of a molten bath covered with molten slag and at this time it is desirable to use short arcs to prevent an excessive amount of heat which 25 would in a short time destroy the side walls and roof of the furnace.

When using a three phase current, a desirable E. M. F. during the refining period is 100 volts. During the melting down 30 period, it is desirable to introduce as much electric power, as measured by kilowatts as possible. With an E. M. F. such as 100 volts and a current of high strength such as 10,000 amperes this is difficult, due to limitation of electrodes, conductors and reactance. 35 Obviously however, it is possible to increase the KWH input without increasing the number of amperes by increasing the voltage.

A higher E. M. F., for instance 150 volts, 40 can be used effectively with the attendant long arc, without injuring the furnace during the melting period, because the arcs used are buried or hidden beneath the scrap. In consequence of these conditions, I provide 45 the necessary connections by which a relatively high E. M. F. can be obtained during the melting down period and then a quick and easy change made to a lower E. M. F. during the refining period. During the refining 50 period, when the lower E. M. F. is used with the correspondingly high current strength it is necessary to eliminate reactance to the greatest possible extent, in order to secure a good power factor, for instance .9, but when using the higher voltage 55 and long arc, the fluctuations of current are

exceedingly great, causing destructive surges on the power line and consequently frequent interruption of the continuity of the arc, thereby decreasing speed in the operation 60 of melting the charge.

My invention provides for the utilization of a relatively high E. M. F. and long arc during the melting down period and a lower E. M. F. and shorter arc during the refining 65 or finishing period, and the introduction of reactance in the primary circuit during the former period to prevent excessive surges on the line and the consequent interruption 70 of the arc.

In the accompanying drawings, Figure 1 illustrates diagrammatically an electric furnace and connections for varying the E. M. F. to thereby give respectively a long arc during the melting down operation and a 75 shorter arc during the finishing operation, by means of adjusting taps on the primary windings of the transformer. In this figure, I have shown what I term a delta-delta combination indicating that the connections 80 of both the primary and secondary windings on the transformer are connected in delta;

Fig. 2 illustrates an alternative arrangement of circuit connections wherein I vary the E. M. F. in the secondary circuit by changing the circuit of the primary connections from delta to star thereby changing the E. M. F. in a ratio of 173 to 100. In this figure the secondary windings of the 90 transformer and the electrodes are connected in star.

Referring to Fig. 1, when it is desired to melt down the charge the three blades of the switch A are closed as shown thereby 95 connecting the primary windings P, P' and P² in delta with the feed wires B, C and D, leading in the case illustrated from a three phase generator.

Connected between the switch A and the 100 feed wires B, C and D by wires b, c and d are reactance coils R, R' and R². With the switch A closed the current from the feed wires flows through the reactances R, R' and R² thereby exciting the primary windings 105 P, P' and P² which are fed by the wires c', d' and b', leading to the adjustable taps T, T' and T² on the transformer, the current returning by way of wires b², c² and d² to the feed wires B, C and D, thus connecting 110 the primary windings in delta combination with the feed wires B, C and D.

Switch A is kept closed for a sufficient time to melt down the charge in the furnace F, the electrodes E, E' and E² at this time being buried beneath the scrap G in the 5 furnace as shown. The electrodes in this instance are connected in delta with the secondary windings S, S' and S² of the transformer as clearly shown in Fig. 1.

After the charge including the scrap has 10 been melted down sufficiently and it is desired to continue the operation of the furnace in order to carry out the finishing or refining operation, the switch A will first be opened and the switch A' will be closed; thereby 15 again connecting the primary coils P, P' and P² in delta with the feed wires B, C and D in a similar manner to that already described excepting that there are no reactances included in the primary circuit and 20 that the current enters the transformer through different taps c¹⁰, d¹⁰ and b¹⁰ returning as before to the feed wires B, C and D by way of wires b², c² and d². By means of adjusting the taps T, T' and T² on the 25 primary coils of the transformer, I am obviously able to vary the E. M. F. induced in the secondary windings in the transformer.

The E. M. F. may be varied either by adjusting the taps on the transformer as above 30 described or by changing the high tension primary connections from delta to star as indicated in Fig. 2 or other phase combinations such as changing the primary connections from star to delta or from delta-delta 35 to star-delta or star-star to delta-star or delta-star to star-star or star-delta to delta-star. It should be understood that when changing by means of taps as shown in Fig. 1 a combination of delta-delta, star-star, 40 delta-star or star-delta may be used as fixed connections in any of the above combinations. I introduce reactance preferably into the primary circuits as illustrated while the higher of the two E. M. F.'s is being used. 45 For controlling the primary circuit combinations, I employ the separate switches A and A' of known type which are interlocked as indicated at L so that both switches must be opened before either can 50 be closed to prevent short circuiting.

In the alternative circuit arrangement illustrated in Fig. 2 the primary and secondary windings are connected in delta-star combination when the switch A is closed 55 and star-star combination when the switch A' is closed, it being understood that in this illustration the electrodes E, E' and E² are connected in star with the secondary windings S, S' and S² of the transformer. In 60 melting down the charge the switch A will be closed thereby cutting in the reactances R, R' and R², and connecting the primary windings P, P' and P² in delta with the feed wires B, C and D, and inducing, for example, an E. M. F. of 173 volts on the sec- 65

ondary windings S, S' and S² of the transformer.

When it is desired to refine or finish the charge in the furnace, the switch A is opened and the switch A' closed thereby 70 connecting the primary windings P, P' and P² of the transformer in star connection with the feed wires B, C and D from the three phase generator.

This current combination will cause a 75 lower E. M. F., for example, 100 volts as compared with the melting E. M. F. of 173 volts. The lower E. M. F. will produce a shorter arc within the furnace, which will not radiate sufficient heat to destroy the 80 side walls and roof of the furnace as would be the case if the higher E. M. F. of 173 volts with a high current strength such as 10,000 amperes were used. When the switch A' is closed the current from feed 85 wires B, C and D enters the primary windings P, P' and P² by way of wires c³, d³ and b³, the opposite ends of the primary coils being connected by wires s, s' and s² to the blades of the switch A' which coat with 90 contacts n, n' and n² connected to the neutral point N of the star connection.

While the arrangements illustrated are for three phase, three wire circuits serving three electrodes, it is to be understood that 95 my invention is applicable to any of the various systems of introducing current into electric furnaces such as single, two phase or three phase, employing either two, three or four wires and with electric furnaces 100 having any number of electrodes and with furnaces either provided with or without bottom connections.

In both figures of the drawing I have shown the reactance arranged on the high tension side of the transformer. It may however be arranged at the low tension side or it may be within the transformer with suitable switches or stops for cutting it in during the melting down operation and out during the refining operation. And instead of providing for a reactance which is entirely in the circuit or entirely cut out of it there may be used an arrangement for cutting in a large reactance during the 110 melting down operation and a smaller reactance during the refining operation. In fact, although I have described with great 115 particularity in detail certain specific embodiments of my invention, yet, it is not to be understood therefrom that the invention is restricted to the particular embodiments disclosed. Various modifications may be made by those skilled in the art without departing from the invention as stated in 120 the following claims.

What I claim is:

1. The method of melting and refining metal in an electric furnace which consists in supplying a current of comparatively 130

high E. M. F. to the electrodes during the melting down period to produce a comparatively long arc and cutting a reactance into the primary circuit to thereby insure continuity of the arc and prevent surges on the power line.

2. The method of melting and refining metal in an electric furnace which consists in changing the E. M. F. from a higher to 10 a lower voltage when performing respectively the melting down and refining operations, reactances being introduced into the circuit at the time the charge is being melted down and the higher E. M. F. used.

15. 3. The methods of varying the KWH input into electric furnaces for melting down and refining the charge which consists in introducing a current of high E. M. F. through a reactance in the circuit to prevent 20 surges on the power line and subsequently cutting out said reactance and introducing a comparatively low E. M. F. during the finishing or refining period.

4. In combination with an electric furnace, circuit arrangements whereby a reactance is introduced in the primary circuit and a comparatively high voltage utilized during the melting down of the charge and means whereby the E. M. F. may be lowered 30 during the finishing operation to vary the intensity of the heat generated at the electrodes to prevent injury to the side walls and roof of the furnace.

5. In combination with electrodes of an 35 electric arc furnace, a transformer and means for varying the voltage impressed on the secondary windings of said transformer and means for cutting reactances into the primary circuit to prevent surges on the

power line, and a consequent interruption 40 in the continuity of the arc.

6. In combination with the electrodes of an electric furnace a transformer and means whereby the E. M. F. and the reactance in the primary circuit may be varied to insure 45 the continuity and vary the intensity of the arc within the furnace.

7. In combination with the electrodes of an electric furnace, a transformer, reactance coils and means whereby the reactance coils 50 may be cut in circuit with windings of the transformer during the melting down of the charge to permit the use of a comparatively high E. M. F. and long arc with a current of great strength without producing excessive 55 current fluctuations or surges on the line, and means whereby a comparatively lower E. M. F. may be impressed on the windings of the transformer to give a shorter arc during a finishing or refining period. 60

8. In combination with the electrodes of an electric furnace, a transformer, reactance coils and means whereby circuit combinations may be effected to include said reactance coils in circuit with the primary windings of said transformer to impress a comparatively high E. M. F. on the secondary winding of the transformer during the melting down operation and means whereby said reactance coils may be cut out of circuit and 70 other circuits made to impress a comparatively lower E. M. F. on the windings of the transformer during the finishing or refining period. 70

In witness whereof, I have hereunto 75 signed my name.

JAMES H. GRAY.
